UNITED STATES PATENT OFFICE.

DERWOOD B. RAFF, OF THOMAS, OKLAHOMA.

WATCH-BALANCE.

1,191,462.

Specification of Letters Patent.

Patented July 18, 1916.

Application filed November 29, 1913. Serial No. 303,795.

To all whom it may concern:

Be it known that I, DERWOOD B. RAFF, a citizen of the United States, residing at Thomas, in the county of Custer and State 5 of Oklahoma, have invented certain new and useful Improvements in Watch-Balances, of which the following is a specification.

It is one of the objects of my invention to prevent a watch balance from getting 10 out of poise and to provide improved means for lengthening or shortening the hair spring to maintain poise without the necessity of adding timing washers or undercutting balance screws.

15 My invention includes the provision of fixed and adjustable collets to which the hair spring is secured and by means of which adjustment of the hair spring can be obtained by the movable collet, only after the hair 20 spring has been released from the fixed collet.

The device of my invention will be more fully described in connection with the accompanying drawing and will be more particularly pointed out and ascertained in and 25 by the appended claims.

In the drawing:—Figure 1 is a view in side elevation looking at the balance cap and illustrating the regulator and hair 30 spring with the balance wheel actuated by the latter. Fig. 2 is a view looking in a direction reverse from the direction from which Fig. 1 is viewed. Fig. 3 is a sectional view on line 3—3 of Fig. 1. Fig. 4 is a sectional view on line 4—4 of Fig. 2.

Like characters of reference designate similar parts throughout the different figures of the drawing.

As illustrated, 1 designates the balance 40 cap of a watch movement in which is journaled one end 2 of a balance arbor. A balance wheel is indicated at 3 and a hair spring at 4. A regulator is shown at 5 and one end of the hair spring 4 is shown fixed 45 to the balance arbor 2, as indicated at 6.

The free end 7 of the hair spring 4 is extended through means which may be in the form of a collet 8, fixed by a screw 16 to the balance cap 1, to permit removal during repair work. The collet 8 is provided 50 with an opening through which the end 7 of the hair spring projects and a screw 9 serves to anchor the hair spring in the collet 8.

The balance cap 2 is provided with a slot 55 10, preferably of arcuate form, in which an adjustable collet is slidably mounted. As shown more particularly in Fig. 3, the adjustable collet is provided with a slot-engaging portion 11, of polygonal cross-section 60 so that it will slidably but non-rotatably engage the walls of the slot 10. Said portion 11 of the adjustable collet is formed integral with a base 12 which is provided with a flange 13 for engagement with one of the 65 side faces of the balance cap 1. A retainer 14 is secured to the adjustable collet, by means such as a screw 15, to engage the other face of the balance cap and retain the adjustable collet in the slot 10. The screw 70 15 also functions to clamp the adjustable collet in place by frictional engagement of the flange 13 and the retainer 14 on opposite sides of the balance cap 1.

The base 12 of the adjustable collet is provided with an opening through which the terminal of the end portion 7 of the hair spring projects and is suitably keyed.

It will be seen from the foregoing, that before the adjustable collet can be moved in 80 either direction in the slot 10, it will be necessary to loosen the hair spring in the fixed collet by turning the screw 9. Thereafter, the adjustable collet can be shifted in the slot 10 to lengthen or shorten the hair spring 85 as desired.

It will be understood that the retainer 14, may in some cases be countersunk in the face of the balance cap 1 for passage of the regulator across or abreast of the adjustable collet in types of movement where this 90 may be necessary.

While I have herein shewn and described one specific form of my invention, I do not wish to be limited thereto except for such 95 limitations as the claims may import.

I claim:—

1. In a watch balance, a balance cap provided with a slot therein, a collet adjustably mounted in said slot, a hair spring having 100 its terminal end keyed to said adjustable collet, and stationary means carried by said balance cap at a point remote from said collet, in the direction of wind of the hair spring for adjustably anchoring said hair 105 spring.

2. In a watch balance, a balance cap provided with a slot therein, a collet adjustably

mounted in said slot, a hair spring having its terminal end keyed to said adjustable collet, and a stationary collet carried by said balance cap adjacent one end of said slot and connecting with the hair spring at a point remote from the adjustable collet with respect to the direction of wind of said hair spring.

3. In a watch balance, a balance cap provided with a slot therein, a collet adjustably mounted in said slot, said adjustable collet comprising a base member and a retainer plate, a hair spring having its terminal end keyed to said adjustable collet and a stationary collet carried by said balance cap adjacent one end of said slot and connecting with the hair spring at a point remote to the adjustable collet with respect to the direction of wind of said hair spring.

20 4. In a watch balance, a balance cap provided with an arcuate slot, a collet slidably fitted in said slot and capable of reciprocal adjustment therein, means for holding said collet in frictional engagement with said balance cap, a hair spring having its terminal end keyed to said adjustable collet and a stationary collet carried by said balance cap, adjacent one end of said slot and

connecting with said hair spring at a point remote from the adjustable collet for adjustably anchoring said hair spring.

5. In a watch balance, a balance cap provided with a slot therein, a two-part collet slidably fitted in said slot and capable of reciprocal adjustment therein, said adjustable collet comprising a base member having a slot-engaging portion and a retainer plate in engagement with the said slot engaging portion, said plate disposed upon the upper face of said balance cap and arranged over said slot, means for connecting said plate and base member and securing the same against the cap to lock the collet in position, a hair spring having its terminal end fixed to said adjustable collet, and means carried by said cap adjacent one end of said slot, and in connection with said hair spring at a point remote from the adjustable collet for adjustably anchoring the hair spring.

45 In testimony whereof I affix my signature in presence of two witnesses.

50 DERWOOD B. RAFF.
